UNITED STATES PATENT OFFICE.

JAMES WILKINSON, OF SCHENECTADY, NEW YORK, ASSIGNEE TO GENERAL ELECTRIC COMPANY, A CORPORATION OF NEW YORK.

INTERNAL-COMBUSTION PUMP.

1,179,593.

Specification of Letters Patent.

Patented Apr. 18, 1916.

Application filed January 14, 1914. Serial No. 812,141.

To all whom it may concern:

Be it known that I, JAMES WILKINSON, a citizen of the United States, residing at Schenectady, county of Schenectady, State of New York, have invented certain new and useful Improvements in Internal-Combustion Pumps, of which the following is a specification.

My invention relates to internal combustion pumps in which the products of combustion act directly on a liquid, and its object is to enable such pumps to operate in a novel way and to improve them in other respects.

15 Various advantages that can be secured in connection with my invention will hereinafter become apparent, and its scope will be indicated in my claims.

In accordance with my invention, I arrange that during the explosion or burning of a combustible charge and the expansion of the products of combustion that constitute a working stroke of the pump the liquid acted on by them shall accumulate or store kinetic or potential energy (or both), and that this energy shall be utilized in producing the desired pump delivery pressure and in compressing one or more of the constituents of another charge. This 20 action can, I find, be secured and utilized to the best advantage by providing a working space or chamber in which the explosion or combustion of the charges occurs and a pump space or chamber proper having inlet and discharge means and connected with the working chamber by passage means so arranged that the liquid can flow freely back and forth through it between the chambers 25 so as to develop kinetic energy and transmit it into potential energy first in one direction and then in the other, somewhat after the manner of a pendulum. I also find that special advantages can be secured by employing a relatively dense or heavy 30 liquid as a medium to accumulate or store kinetic or potential energy and to transmit the force of the expanding products of combustion to the fluid to be pumped: among the advantages thus obtained I may mention 35 the ability to secure a high speed of operation as compared with what is possible when the energy is accumulated or stored by a liquid of lower specific gravity.

I have hereinafter shown and described 40 several forms of pumping apparatus constructed in accordance with my invention

in which mercury is used as a liquid medium for operating upon the fluid to be pumped. These types of apparatus are adapted to receive water or other liquid or air or other gas or vapor at pressures either above or below atmospheric and to deliver against either high or low heads. They are also adapted to the use of almost any fuel,—as producer gas, gasolene, or other gas or vapor; crude oil or other liquid; or coal dust or other solid, etc. While, however, the forms of apparatus shown and described are the best for the purpose of my invention at present known to me, and while the invention extends to these forms of apparatus and to their specific features and details of operation and construction and their various novel combinations and arrangements of parts, yet the invention is not confined thereto or to the use of mercury, but can be carried out in other ways.

In the accompanying drawing, Figure 1 is a sectional view of a pumping apparatus constructed in accordance with my invention, various parts being broken out and removed to bring the apparatus as a whole within the limits of the paper. This apparatus is especially suitable for pumping against low or moderate heads. Fig. 2 is a diagrammatic sectional view illustrating the main features of a modified form of apparatus more suitable for pumping against high heads than that apparatus shown in Fig. 1. Fig. 3 is a similar diagrammatic sectional view illustrating the main features of another modified form of apparatus. Fig. 4 is a fragmentary diagrammatic sectional view illustrating the operation of the form of apparatus shown in Fig. 3.

In the apparatus shown in Fig. 1 there is a casing part 1 containing an upright cylindrical combustion or working chamber 2 and a similar pumping chamber 3, and there is also conduit means containing a U passage 4 connecting the lower ends of these chambers. As shown, the chambers 2 and 3 are of substantially the same dimensions, while the passage 4 is considerably smaller in cross-section than either of them; but it will be understood that these proportions may be widely varied. The working chamber 2 has inlet means 5 for the introduction of operating fluid comprising air and fuel opening into its upper end and exhaust means 6 for the discharge of spent products of combustion opening from its

- lower end, and the pump chamber 3 has intake and discharge means 7 and 8 for the water or other fluid to be pumped, both opening into its upper end. Although under suitable conditions of operation the combustion in the working chamber 2 can be brought about as a result of compression of the operating fluid therein, this particular apparatus has electric ignition means at the upper end of said chamber for producing or insuring ignition at the proper time. The inlet means 5 for air and fuel, the exhaust means 6, and the ignition means 9 are all associated with a removable top or cover 10 at the upper end of the chamber 2. There is also an opening 11 into the chamber 2 for the introduction of compressed air or the like for starting purposes or for the introduction of mercury or other liquid as required.
- It will be seen that the water intake means 7 and discharge means 8 both open into an intake and discharge chamber 12 in a separate casing part mounted on top of the casing 1 and opening downward into the chamber 3,—the former through a spring actuated inwardly opening check valve 13 and the latter through a similar outwardly opening check valve 14.
- It will be seen that the apparatus contains sufficient mercury to fill the working chamber 2 and the passage 4, and that on top of the mercury in the working chamber is a layer of water, oil, or other suitable liquid to protect the same against oxidation or the like.
- The air and fuel inlet passage open directly downward through the cover 10 and has beneath it a sort of hood 15 which gives the incoming fluid a whirl that tends to insure complete filling of the upper part of the chamber 2 thereby and to remedy any lack of uniformity in the previous mingling of its constituents. The inlet means 5 also includes a valve 16 that seats over the mouth of the air and fuel passage within the hood 15 and a float 17 of iron or other suitable material arranged in the lower part of the chamber 2 and connected with the valve 16 by a rod 18 on which it is adjustably mounted. This float 17 responds to the fall and rise of the mercury in the chamber 2, and thus the admission of air and fuel is controlled by the movements of the mercury, as hereinafter described. As shown, the upper end of the rod 18 extends up through the cover 10 so that when the pump is in operation its movements can be observed and the speed of the pump determined.
- The exhaust means 6 for spent products of combustion comprises a pipe or tube 20 extending through the cover 10 and downward in the center of the working chamber 2 nearly to its bottom, where it terminates just over the opening into the passage 4.
- In the lower end of this exhaust pipe 20 is a deflector 21 which without unduly restricting the opening obviates the tendency that would otherwise exist for mercury flowing into the chamber 2 from the passage 4 very rapidly to shoot straight up the pipe. A little above the deflector 21 there are a number of downwardly and outwardly inclined holes 22 through the wall of the pipe 20; these holes 22 are about at the level at which the falling mercury will cause the float 17 to open the air and fuel valve 16, so that when on the working stroke the uncovering of these holes by the mercury allows the spent products of combustion to escape into the exhaust pipe 20 fresh air and fuel will rush in to take their place and thus, as it were, scavenge the working chamber. At the upper end of the exhaust pipe 20 is a spring mounted outwardly opening check valve 23. The spring beneath this valve 23 is just strong enough to balance its weight, so that it will open when the pressure in the pipe 20 exceeds that of the region into which said pipe opens and close when these conditions are reversed.
- The electric ignition device 9 comprises a stationary contact or electrode bridge piece 24 extending across the lower end of a cylindrical bore in the cover 10; a movable contact or electrode 24^a carried by a piston 25 in said bore but suitably insulated therefrom; and a helical spring 26 between the piston and a screw plug 27 in the upper end of the bore that tends to force the piston downward and for most of the time keeps the electrodes in contact. The electrodes 24 and 24^a are connected by wiring 28 with a suitable source of current 29, so that when the gas or vapor pressure in the working chamber causes their separation at the proper time an arc or a spark shall occur between them. Accumulation of gas or vapor above the piston 25 to such an extent as to interfere with this action may be prevented by making the opening in the plug 27 through which passes the conductor 30 directly connected with the movable electrode 24 large enough to serve as a vent.
- I will now describe the operation of the apparatus: The condition shown is that at or about the end of the return or suction stroke,—the mercury in the working chamber 2 being at substantially its highest level with a charge of air and fuel compressed above it and that in the exhaust pipe 20 being higher to an extent approximately corresponding to the compression of the charge, the air and fuel inlet valve 16 being closed, and the exhaust valve 23 being open or about to open for the exhaust of the spent products of combustion from the previous working stroke; the pump chamber 3 being full of water and the water intake and discharge valves 13 and 14 being closed.

closed and the piston 25 having begun to rise under the pressure of the charge so that the device 9 is in the act of igniting it or has just done so. Immediately after the 5 explosion, the expanding products of combustion (aided by the potential energy of the mercury represented by the height thereof in the working chamber 2 above its level in the pump chamber 3) will force the 10 mercury down in the working chamber 2 and cause it to rise in the exhaust pipe 20 to a height approximating or even exceeding that corresponding to the explosion pressure and thus expel the greater part of 15 the spent gases therefrom. At the same time, the mercury will also be forced through the passage 4 into the pump chamber 3, pushing the water therein out through the discharge 8. When the pressure 20 in the chamber 2 has fallen sufficiently and the mercury column in the exhaust pipe 20 has used up about all of its upward momentum in drawing up more mercury behind it and in forcing out spent gases ahead 25 of it, the mercury in the pipe 20 will begin to fall, for the most part passing down around the baffle 21 right into the passage 4 and so acquiring considerable momentum and aiding in the forcing out of water from 30 the pump chamber 3. As the column of mercury falls, the exhaust check valve 23 will close and a partial vacuum will be formed in the upper end of the exhaust pipe. By the time almost all of the water 35 in the pump chamber 3 has been driven out and the kinetic energy of the mercury has been almost entirely expended or converted into potential energy (represented by its height in the pump chamber 3 above its level in the working chamber 2), the mercury around and within the exhaust pipe 20 will uncover the holes 22, whereupon the 40 products of combustion will rush through them into the exhaust pipe,--this action being aided by the vacuum therein and by the scavenging action of the air and fuel admitted through the valve 16. The coming to rest of the mercury at this time or shortly 45 after will conclude the working stroke. The unbalanced weight of the mercury in the pump chamber 3 will now bring about a reverse movement or return stroke, the mercury falling in the pump chamber 3 and rising in the working chamber 2 and 50 in the exhaust pipe 20. During the return stroke, the mercury will suck water into the pump chamber 3 from the intake 7 (or allow it to flow in of itself), close the air and gas inlet valve 16 in the working chamber 55 2 and thereafter compress the air and gas in said chamber, and raise the pressure of the spent products of combustion in the exhaust pipe 20 or even force some of them out through the exhaust valve 23. In this 60 manner the conditions at the beginning of the working stroke will eventually be restored whereupon the device 9 will again act to produce ignition, and another working stroke will ensue.

In the foregoing description of an ordinary cycle of the pump a previous initial starting of the apparatus into operation is assumed. It will readily be seen, however, that when the pump stops special measures 70 may be necessary to start it into operation. If, for example, the stoppage was due to a failure or shutting off of the supply of air or of fuel (or of both), the working chamber 2 will probably contain cold products of combustion under a certain degree of pressure. To start the pump under these conditions, air under pressure may be forced 75 into the chamber 2 through the opening 11 so as to produce a sort of artificial working stroke ending with an exhaust and an admission of air and fuel and followed by a normal return stroke and ignition; or, alternatively, a valve 31 in the discharge 8 may be temporarily closed and water or air under pressure may be forced into the water 80 intake and discharge chamber 12 and the pump chamber 3 through the opening 32 so as to compress the gas in the working chamber 2 and force the mercury up nearly to the top of the exhaust pipe 20,—after which the 85 opening of the valve 31 will be followed by an artificial working stroke and a normal return stroke and ignition, as in the other method. If, on the other hand, the stoppage 90 of the pump was due merely to failure or cutting off of the ignition current, there will probably be a charge of air and fuel in the working chamber 2 under slight compression; and in this case it may be possible to start the pump by merely turning on the 95 current and drawing up the piston 25 by means of its insulated current supply conductor 30 so as to cause ignition of this charge, without any of the other measures 100 above described.

Referring, now, to the high head pump shown in Fig. 2, it will be seen that while the main features of the apparatus are the same, the relative height and cross-section of the working chamber 42 and the pump 105 chamber 43 are such that the range of movement or stroke of the mercury in the latter is about three times as great as in the former. In consequence of this there will be a differential speed relation in the movement of 115 the mercury in the chambers 42 and 43, and therefore the total kinetic energy of the mercury will be very much greater if a suitably heavy charge of fuel is used without the stroke in the working chamber 42 being 120 excessive. It will also be observed that in this apparatus the air and fuel valve 46 is held shut by a spring, so that its opening 125 will be caused by the drop in pressure in the working chamber 42 about as the ex- 130

haust begins instead of by the mercury itself, and that the ignition device 49 is adapted to be controlled otherwise than by the pressure in the working chamber. It will be seen that this pump receives oil from a well or tank 70 open to the atmosphere at 71 and delivers the oil to a closed reservoir or accumulator 72 which affords both oil storage and air cushion space and so eliminates or reduces fluctuations in the pressure of the oil due to the intermittent action of the pump. From this reservoir 72 the oil is conveyed through piping 73 to an oil turbine 74, whence it flows back to the oil tank 70. As both the pump and the oil turbine can be constructed to give a very high efficiency, such a system is a very economical one for the production of power.

Referring, now, to Fig. 3, it will be found that the apparatus differs from that shown in Fig. 2 principally as regards the exhaust. As shown, the exhaust pipe 50 is freely open at both ends and has no holes corresponding with the holes 22 shown in Fig. 1, and beneath the flared open lower end of the pipe 50 is a ball float valve 51 of iron, steel, or other suitable material adapted to be seated pressure tight thereon and to prevent entrance of the mercury thereinto at any stage of operation during which it might otherwise occur. When at the end of the working stroke the mercury falls low enough in the working chamber 52, the ball 51 will drop away and open the pipe 50 to the exhaust, and, as shown in Fig. 4, it may then be allowed to seat pressure tight on the bevelled opening into the passage 54, so that the vacuum which further movement of the mercury in the latter will produce beneath said valve may both check or damp any tendency for an excessive rise of the mercury in the pump chamber 53 and help the head thereof in said chamber to start the mercury quickly into motion on the return stroke. It will be seen that in this apparatus the ignition device 69 is similar to that shown in Fig. 1, and that a float 60 connected by a rod 61 with an indicator 62 in a transparent walled chamber 63 serves as a clearance indicator to show the height to which the mercury rises in the working chamber 52.

I do not herein claim the power system hereinbefore described, since the same is embraced in my application Serial No. 812140, filed Jan. 14, 1914, concurrently herewith.

In accordance with the provisions of the patent statutes, I have described the principle of operation of my invention, together with the apparatus which I now consider to represent the best embodiment thereof; but I desire to have it understood that the ap-

paratus shown is only illustrative, and that the invention can be carried out by other means.

What I claim as new and desire to secure by Letters Patent of the United States, is,—

1. An internal combustion pump comprising a working chamber having inlet means for the constituents of a combustible charge and exhaust means for spent products of combustion, a pump chamber having inlet and discharge means for fluid to be pumped, and passage means connecting said chambers independently of the pump chamber inlet and discharge through which liquid may flow freely back and forth between them and so freely develop momentum.

2. An internal combustion pump comprising a working chamber having inlet means for the constituents of a combustible charge and exhaust means for spent products of combustion, a pump chamber having inlet and discharge means for fluid to be pumped, means affording free passage independently of the pump chamber inlet and discharge connecting said chambers, and a body of liquid relatively heavy as compared with the fluid to be pumped adapted to flow back and forth between them through said free passage and so freely develop momentum.

3. An internal combustion pump comprising an upright working chamber having inlet means for the constituents of a combustible charge and exhaust means for spent products of combustion, an upright pump chamber having at its upper end inlet and discharge means for fluid to be pumped, means affording a free passage connecting the lower ends of said chambers, and a body of mercury adapted to flow back and forth between the chambers through said free passage and so freely develop momentum.

4. An internal combustion pump comprising an upright working chamber having at its upper end inlet means for the constituents of a combustible charge and at its lower end exhaust means for spent products of combustion, an upright pump chamber having at its upper end inlet and discharge means for fluid to be pumped, a U connection between the lower ends of said chambers affording a free passage back and forth between them, and a body of fluid relatively heavy as compared with the fluid to be pumped adapted to flow back and forth between them through said free passage and so freely develop momentum.

In witness whereof, I have hereunto set my hand this 12th day of January, 1914.

JAMES WILKINSON.

MARGARET E. WOOLLEY.

Corrections in Letters Patent No. 1,179,593.

It is hereby certified that in Letters Patent No. 1,179,593, granted April 18, 1916, upon the application of James Wilkinson, of Schenectady, New York, for an improvement in "Internal-Combustion Pumps," errors appear in the printed specification requiring correction as follows: Page 1, line 89, for the word "that" read *the*; page 2, line 72, for the reference numeral "34" read *21*; and that the said Letters Patent should be read with these corrections therein that the same may conform to the record of the case in the Patent Office.

Signed and sealed this 16th day of May, A. D., 1916.

{SEAL.}

J. T. NEWTON,

Acting Commissioner of Patents.
